(57) **CLAIM**

The ornamental design for a cleaning supply tote as shown and described.

DESCRIPTION

FIG. 1 is a top front side perspective view of a cleaning supply tote showing my new design;

FIG. 2 is a top front side perspective view of the cleaning supply tote in an alternative position;

FIG. 3 is a front view of the cleaning supply tote;

FIG. 4 is a rear view of the cleaning supply tote;

FIG. 5 is a left side view of the cleaning supply tote;

FIG. 6 is a right side view of the cleaning supply tote;

FIG. 7 is a top view of the cleaning supply tote; and,

FIG. 8 is a bottom view of the cleaning supply tote.

The evenly spaced broken lines shown in FIGS. 1 and 7 depict environmental subject matter, and form no part of the claimed design.

1 Claim, 7 Drawing Sheets(56)
